(57) **CLAIM**

The ornamental design for a carpal tunnel brace, as shown and described.

DESCRIPTION

FIG. 1 is a perspective view of the carpal tunnel brace in use, the broken line showing of the hand is for illustrative purposes only and forms no part of the claimed design; FIG. 2 is a perspective view thereof; FIG. 3 is a perspective view thereof with an optional strap in broken lines, the broken line showing of the strap is for illustrative purposes only and forms no part of the claimed design;

FIG. 4 is a top view thereof with the two pressure adjustment straps extended;

FIG. 5 is a cross-sectional view taken along line 5—5 of FIG. 10, looking down towards the lower half thereof;

FIG. 6 is a bottom view thereof;

FIG. 7 is a right side view thereof;

FIG. 8 is a left side view thereof;

FIG. 9 is a front view thereof; and,

FIG. 10 is a rear view thereof.
